ATTORNEY.

UNITED STATES PATENT OFFICE.

CHARLES T. SHAVER, OF SPRINGFIELD, OHIO, ASSIGNOR TO THE WESTERN MANUFACTURING COMPANY, OF SPRINGFIELD, OHIO, A CORPORATION OF OHIO.

TOOL-HOLDER.

SPECIFICATION forming part of Letters Patent No. 708,176, dated September 2, 1902.

Application filed April 11, 1901. Serial No. 55,289. (No model.)

To all whom it may concern:

Be it known that I, CHARLES T. SHAVER, a citizen of the United States, residing at Springfield, in the county of Clark and State of Ohio, have invented certain new and useful Improvements in Tool-Holders, of which the following is a specification, reference being had therein to the accompanying drawings.

This invention relates to tool-holders for lathes, &c., and has for its object to provide a simple and efficient construction whereby the tool may be readily and firmly clamped in position in the tool-holder, so as to prevent "chattering" or vibration of the tool when in use.

To these and other ends the invention consists in certain novel features, which I will now proceed to describe and will then particularly point out in the claims.

In the accompanying drawings, Figure 1 is a plan view of a tool-holder embodying my invention in one form. Fig. 2 is a side elevation of the same. Fig. 3 is a rear end view. Fig. 4 is a front end view. Fig. 5 is a sectional view taken on the line $x-x$ of Fig. 2 and looking in the direction of the arrows. Fig. 6 is a plan view illustrating a modification, and Fig. 7 is a sectional view taken on the line $y-y$ of Fig. 6 and looking in the direction of the arrows.

In the construction shown in Figs. 1 to 4, inclusive, I have illustrated my invention in its preferred form, and I have also shown it as applied to what is known as a "straight" tool-holder. In this construction, 1 indicates the shank of the holder, which is of the usual conformation to adapt it to be held in the usual manner in the tool-post of a lathe or the like. At its forward end this shank is provided with a head 2, preferably of greater width than the shank and having at one side thereof a recess or seat 3 of such shape to adapt it to receive the tool 14, which in the present instance is a cutting-off tool having a flat body. At its lower end this seat or recess terminates in a shoulder or flange 4, against which the lower edge of the tool rests, said shoulder or flange being undercut, so as to prevent lateral movement of the lower edge of the tool, and this undercutting being preferably effected upon an incline or bevel, as

shown. The lower edge of the tool will be correspondingly shaped to fit the undercutting of the shoulder 4, and where bevels or inclines are employed no particular nicety of fitting is required, as the tool will properly seat itself against the face of the recess or seat regardless of minor differences in the dimensions of the parts. In conjunction with the head I employ a cap 5, which is supported on the head and which extends out over the top of the recess 3, as indicated at 6, and is provided on that side with a depending flange 7, between which and the face of the recess 3 the upper edge of the tool is embraced. In the preferred form of construction (shown in Figs. 1 to 5) the head 2 is provided on that side thereof opposite to the side which has the recess 3 with an inclined bearing-surface 8, while the cap 5 is provided with a correspondingly-inclined downwardly-extending flange 9, adapted to engage said bearing-surface. The cap is secured to the head by any suitable means, that which I prefer consisting of a clamping-screw 10, passing through a slot 11 in the cap and taking into a threaded aperture 12 in the head. The slot 11 is preferably inclined in the same direction as the bearing-surface 8 and flange 9. In the case of a straight tool where the head has its seat in line with the shank 80 said seat continues along the side of the shank, as indicated at 13. It will be seen that when the tool is placed in position and the cap is moved rearward along the head or in the direction of the shank the engagement of the 85 inclined bearing-surfaces of the cap and head will cause the flange 7 to engage with the upper edge of the tool 14 and clamp the same firmly against the face of the recess 3, the part being secured in this position by the 90 clamping-screw 10, and the lower edge of the tool being already firmly held by the undercut shoulder 4, so that chattering or vibration of the tool will be prevented. The release of the tool may be as readily effected by 95 loosening the screw 10, whereupon a slight forward movement of the cap will disengage the tool. It will be further seen that the construction is such that tools of various thickness may be employed in the same holder, as 100 the cap will readily adjust itself to the thickness of the tool without affecting its efficiency.

as a clamping device. It will be understood, of course, that the cap also exerts a downward pressure upon the tool, so as to press the same firmly downward against the shoulder 5 4, where the tool is of sufficient height to extend to or above the top of the head 2.

The inclined bearing-surfaces of the cap and head may be otherwise constituted than in the manner just described and shown in 10 Figs. 1 to 5, inclusive, and in Figs. 6 and 7 I have shown a modified construction, which, incidentally, is illustrated as applied to what is known as an "offset" tool-holder. In this construction the head 15 is placed at an angle to the shank 16, and the lateral seat 17, provided with the undercut shoulder 18, is formed in the head only and does not extend along the shank. In this construction the cap, which is indicated at 19, extends over 15 the seat in the manner already described and has the clamping-flange 20, corresponding with the flange 7 of the construction shown in Figs. 1 to 5. The inclined bearing-surfaces are in this case furnished by the slots 20 21, formed through the cap for the passage of the clamping-screws 22, which take into threaded apertures in the head. The inclination of these slots is such that movement of the cap relatively to the head in the proper 25 direction will draw the flange 20 against the upper edge of the tool and serve to clamp it against the seat, where it may be held by tightening the screws 21. It will be noted that in Figs. 6 and 7 the cap is shown as resting upon the top of the head instead of embracing both edges thereof, and I prefer to cut away the under surface of the cap, as indicated at 23, thus forming a flange 24 along that edge of the cap opposite to the edge on 30 which the clamping-flange 20 is formed, so that the cap bears upon the head with this marginal flange 24 only, and is thereby better adapted to tools of differing heights.

Tool-holders of this character are ordinarily constructed of comparatively soft metal, which is apt to be injured or defaced by the clamping-screw of the tool-post in which the holders are held, and in order to obviate this difficulty I propose to permanently secure to 45 the top of the shank a plate 25, of hard metal, constituting a wearing-plate against which the clamping-screw of the tool-post will impinge and which will serve to protect the shank of the holder from injury or defacement, and thereby increase the durability of 50 the holder. Where such a clamping-plate is applied to a straight holder, as shown in Figs. 1 to 5, I prefer to have the plate extend over the recess or seat 13 in the shank, so as 55 to give an additional holding means for the tool. Where the wearing-plate extends as far forward as possible, as in the construction shown in Figs. 1 and 2, the rear end of the cap may be undercut, as indicated at 26, so 60 as to extend over the end of the plate without affecting the clamping functions of the cap.

I do not wish to be understood as limiting myself to the precise details of construction hereinbefore described, and shown in the accompanying drawings, as these details may obviously be modified without departing from the principle of my invention.

Having thus fully described my invention, what I claim as new, and desire to secure by Letters Patent, is—

1. A tool-holder having a lateral recess or seat in its head, terminating at the bottom in a shoulder or flange, undercut to receive and prevent lateral movement of the lower edge of the tool, in combination with a cap supported on said head, extending over the top of said recess or seat, and provided with a depending flange to engage the outer face of the tool at its upper edge, and means for adjustably securing said cap on said head, said means comprising engaging surfaces on the head and cap, one of which is inclined to the face of the seat or recess, whereby, when the cap is moved longitudinally on the head, its depending flange will be pressed against the upper edge of the tool, substantially as described.

2. A tool-holder having in one side of its head a lateral recess or seat, terminating at the bottom in a shoulder or flange, undercut to receive and prevent lateral movement of the lower edge of the tool, the opposite side of the head being provided with a bearing-surface inclined to the plane of the recess or seat in the first-mentioned side, a cap adjustably supported on said head and extending beyond both sides thereof, being provided on the recessed side with a depending flange to engage the outer face of the tool at its upper edge, and having on the opposite side of the head a depending flange to engage the inclined bearing-surface of said side, and means for securing said cap in position on the head after adjustment, substantially as described.

3. A tool-holder having in one side of its head a lateral recess or seat, terminating at the bottom in a shoulder or flange, undercut to receive and prevent lateral movement of the lower edge of the tool, the opposite side of the head being provided with a bearing-surface inclined to the plane of the recess or seat in the first-mentioned side, a cap adjustably supported on said head and extending beyond both sides thereof, being provided on the recessed side with a depending flange to engage the outer face of the tool at its upper edge, and having on the opposite side of the head a depending flange to engage the inclined bearing-surface of said side, and means for securing said cap in position on the head after adjustment, said means comprising a slot in the cap parallel with the inclined bearing-surface, and a clamping-screw passing through said slot into the head, substantially as described.

4. A tool-holder comprising a head and shank, both having formed in them a continuous lateral recess or seat, terminating at

the bottom in an undercut shoulder or flange to receive and prevent lateral movement of the lower edge of the tool, in combination with a clamping-cap mounted on the head 5 and adapted to grip the upper edge of the tool, and a flat wearing-plate, of harder material than the shank, permanently secured on the top of the shank and extending laterally beyond the same over the top of the re-

cess or seat therein immediately above the 10 tool, substantially as described.

In testimony whereof I affix my signature in presence of two witnesses.

CHARLES T. SHAFER.
